Application March 9, 1935, Serial No. 10,147

4 Claims. (Cl. 201—48)

This invention relates to rheostats for regulating the flow of electric current, and has for its general object the provision of a novel rheostat in which the variation of an electric current through a large number of incremental steps is accomplished by a very compact and simple construction.

Another object of the invention is to provide an improved rheostat in which the full regulatory range thereof through a large number of incremental steps is covered by a small relative motion of the coacting parts.

A further object of the invention is to provide an improved rheostat in which the resistance unit as a whole comprises a plurality of resistance elements which are mounted for ready removability and interchangeability so that any desired resistance range may be obtained by selection of the proper combination of elements and incorporation thereof in the rheostat structure.

Another object is to provide an improved rheostat comprising a resistance unit and a contactor unit mounted for relative movement wherein the separate resistance elements are mounted in spaced groups and a plurality of contacting devices are spaced in conformity with the spacing of the groups of resistance elements to coact therewith; the arrangement being such that upon relative motion of the two units the contact devices are progressively carried into coaction with the elements of each group and are successively brought into association with the respective groups of resistance elements whereby a wide range of current variation through small incremental steps is accomplished by a small relative movement of the two units.

Other objects and advantages of the invention will become apparent from the following detailed description of a preferred embodiment thereof taken in connection with the accompanying drawings, in which:

Figure 1 is an elevational view, partly in section, of a rheostat embodying the features of the invention.

Fig. 2 is a sectional view of the rheostat taken along the line 2—2 of Fig. 1.

Fig. 3 is a partial sectional view of one of the resistance elements.

Fig. 4 is a fragmentary view, partly in section, taken on the line 4—4 of Fig. 2 and showing the manner in which the resistance elements are alined in their supporting disk.

Fig. 5 is an elevational view taken on the line 5—5 of Fig. 2 with the casing shown in section.

Fig. 6 is a sectional view taken on the line 6—6 of Fig. 5.

Fig. 7 is a sectional view taken along the line 7—7 of Fig. 4.

Figs. 8 to 12, inclusive, are views showing the relative positions of the contact arms and the resistance elements as the contact mechanism is actuated from the position of maximum resistance to the position of minimum resistance.

While the invention is susceptible of various modifications and alternative constructions, I have shown in the drawings and will herein describe in detail a preferred embodiment, but it is to be understood that I do not thereby intend to limit the invention to the specific form disclosed, but intend to cover all modifications and alternative constructions falling within the spirit and scope of the invention as expressed in the appended claims.

The rheostat shown in the drawings for purposes of illustration is of the parallel resistance type having a resistance unit and a contact mechanism mounted for relative rotary movement. Generally stated, the resistance unit comprises a supporting member upon which individual resistance elements are mounted with one of their ends electrically common and the other ends terminating in contacts which are mounted for individual yielding movement and grouped in a plurality of rows. To render the resistance elements readily interchangeable and quickly removable, each preferably comprises a rigid rod carrying one of said contacts at one end.

The contact mechanism which preferably is the movable part of the rheostat, comprises a series of contact plates the leading edges of which are positioned so that in the continued movement of the mechanism the contacts in one row are engaged successively, then the successive contacts of another row are engaged, and so on until all of the resistance elements have been interposed in the electric circuit.

More specifically described, the resistance unit in the preferred embodiment comprises a plurality of resistance elements in the form of rigid rods 13 removably mounted in parallel apertures formed in a stationary supporting member 14 (Fig. 2) comprising two plates 15 and 16 of insulating material such as bakelite and spaced apart by projecting pads 17 (Fig. 7) which are held together by screws 18 threading into tapped holes in the pads on the plate 16.

The plates are formed with coaxially alined apertures 19 arranged in substantially radially disposed, angularly spaced rows A, B, C, D, E, 55

- and F, for the reception of the resistance elements 13. The rows are arranged in angularly spaced pairs of groups with a materially greater spacing between the rows in the same group.
- 5 Each of the rows, in the present instance, comprises five apertures having their respective axes disposed in planes intersecting at the axis of the unit, but progressively spaced from each other as shown in Fig. 4.
- 10 The apertures in the plate 15 are closed at one end by a segmental contact member 20 (Figs. 2 and 5) secured tightly against the outer face of the plate by the screws 18 which hold plates 15 and 16 together and by a bolt 21 (Figs. 5 and 6) which extends through the plate 15 and the member. A nut 22 threaded on the bolt 21 engages the member 20 and provides an electrical connection between the member and the bolt, the latter serving as one binding terminal 20 of the rheostat.
- 15 The individual resistance elements 13 disposed in the apertures are electrically connected with the member 20 through the compression springs 23, thereby making the elements electrically connected at one end. The springs are so proportioned that they urge the resistance elements 24 into contact with the face of a contact mechanism 24 which abuts against the outer face of the plate 16.
- 20 The resistance elements 13 (Fig. 3) comprise rods of resistance material such as compressed carbon having ends over which are pressed metallic cups 13^a which serve as connecting terminals or wear-resisting contacts for the elements. Being entirely independent of each other and removably mounted, the resistance elements 13 may be constructed to have various resistance values and adapted for ready interchangeability whereby the current regulating characteristics of 40 the rheostat may be altered to suit the particular requirements of different circuits.
- To provide a second terminal for the rheostat, the plates 15 and 16 of the resistance unit are provided with an additional pair of axially aligned apertures 25 (Fig. 6) which are located between the rows B and C and somewhat closer to the latter row. Within this aperture is mounted a metallic rod 26 electrically connected by a pigtail conductor 27 with a segmental conductive plate 28 secured to the outer face of the plate 15. A spring 29 bearing against the plate 28 urges the rod into engagement with the face of the contact mechanism 24. The segment 28 is secured to the plate 15 by one of the screws 18 which hold the plates 15 and 16 together and by a bolt 30 which extends through the plate and segment. A nut 31 threaded on the bolt 30 tightly engages the segment and provides an electrical connection between the segment and the bolt which constitutes the second binding terminal for the rheostat.
- 35 The plates 15 and 16 which constitute the supporting frame of resistance unit of the rheostat are held against rotation in a cylindrical casing 32 by bars 33 (Fig. 5) attached to the internal wall of the casing and entering segmental slots 33^a (Fig. 8) in the peripheral edges of the plates. The unit is further secured to the casing by the bolts 21 and 30 which extend through holes in 45 a cover plate 34 and are insulated therefrom by insulating bushings 31 (Figs. 2 and 6). The cover plate is detachably secured to the casing by nuts 39 threaded onto the ends of the bars 33 which project through apertures in the cover.
- 50 Coacting with the stationary resistance unit

above described, is the rotatable contact mechanism 24 disposed within the casing 32 in engagement with the face of the plate 16 and the contacts 13^a on the ends of the resistance elements 13. The contact mechanism comprises, in the present instance, a metallic contact member 40 (Figs. 2, 6, and 8) set into the face of a support plate or disk 41 of suitable insulating material so that the surface of the member 40 is flush with the surface of the disk and segmental arms or sectors 42, 43, and 44 project radially from a central hub. The arms are so proportioned that, in the normal open circuit position of the contact mechanism (Fig. 1), the arm 42 will just fit between the rows of elements A and F and out of contact therewith. At the same time, arm 43 will be disposed between the rows B and C with its leading edge separated from the innermost element of row C by a space equal to the width of a resistance element plus a slight clearance. The arm 44 normally lies between rows D and E and its leading edge is separated from the innermost element of row E by a space equal to twice the width of a resistance plus a slight clearance. Each of the arms is wide enough to maintain contact with all of the elements of the two rows with which it is associated.

In order to provide for contacting the individual resistance elements one by one incidental to small incremental steps in the rotation of the contact mechanism, the leading edges of the contact arms 42, 43 and 44 are formed in planes inclined with respect to the rows of contacts. In the present instance, the contact rows are inclined with respect to the radii of their supporting disks and, since the contact member is axially aligned with the disks, the leading edges of the arms may be disposed substantially radially. The edges of the arms thus approach the respective contact rows at an angle such that the elements of each row are contacted in succession.

The angular spacing of the contact rows is such that all of the elements of one row are contacted and then the elements of the next alternate row are contacted. Thus, the elements of row A are first contacted successively by the arm 42 and then the elements of row C are contacted successively by the arm 43. Next the elements of row E are contacted successively by the arm 44 followed by engagement of the arm 42 with the successive elements of row B and engagement of the elements of row D by the arm 43, the elements of row F being finally contacted successively by the arm 44. In this manner a different resistance element is contacted in response to each movement of the contact mechanism through a small angle until all of the elements have been connected in circuit. In the illustrative embodiment of the invention, all of the resistance elements are connected in the circuit incidental to the contact mechanism rotating through an angle of approximately forty-five degrees.

The contact mechanism 24 is rotated by means of an operating member or link 45 (Fig. 1) operatively connected with a mechanism supporting shaft 46 by a lever arm 47. The shaft is suitably journaled at one end in the stationary plates 15 and 16 of the resistance unit and is provided with a square shoulder 48 (Fig. 2) intermediate its ends which engages a square hole in the disk 41 of the contact mechanism. A collar 49 formed integral with the square shoulder 48 and at one end thereof bears against a shoulder formed on the disk 41 and, in cooperation with a washer 50

- bearing against the plate 15 of the resistance unit and held in place by a lock nut 51 threaded on the end of the shaft, maintains the contact mechanism and resistance unit in tight engagement.
- 5 The other end of the shaft 46 is journaled in a bearing 52 carried by the casing and is provided with a rigid arm 47 operatively connected with the link 45 whereby reciprocation of the link is enabled to effect the rotation of the shaft 46
- 10 and contact mechanism 24. The limit of rotation of the mechanism is defined by shoulders 56 and 57 (Fig. 1) engaging the bars 33 on the inner wall of the casing.
- In operation, the rheostat is connected in a circuit to be controlled by attaching the circuit conductors to the respective terminals 21 and 30. The circuit will be open at the rheostat with the same in normal condition as shown in Fig. 1 since the various contact blades 42, 43, and 44 will be 20 out of contact with their associated resistance elements.

To effect the initial closure of the circuit, the link 45 is shifted slightly to the left as shown in Fig. 1 which rotates the contact mechanism 24 25 in a clockwise direction. This rotation of the mechanism first brings the blade 42 into engagement with the innermost element 13 of the row A thereby completing the circuit through this element. The portion of the circuit within the 30 rheostat then extends from the terminal 21, conductive segment 20, spring 23 and resistance element 13 in the innermost position of row A, blade 42 of the contact member, contact member 40, blade 43, contact rod 26, conductive segment 28 35 to the terminal 30. The circuit has its maximum resistance value under these conditions as only one of the resistance elements is included therein.

The circuit resistance will be progressively decreased in small steps as the continued rotation 40 of the contact mechanism 24 brings the contact arms into contact with the resistance elements 13 successively and connects these elements in parallel with the first element 13 of row A. The circuit will have its minimum resistance value when 45 the contact mechanism reaches its limiting position and all of the elements 13 are connected in parallel in the circuit.

The circuit is restored to its normal open position by the shifting of the link 45 to the right as 50 viewed in Fig. 1. The contact mechanism is rotated in a clockwise direction and the resistance elements are successively disengaged from the contact arms. Thus, the circuit resistance is increased in small steps until it reaches a condition 55 of maximum resistance after which it is opened by the disconnection of the last resistance element 13 therefrom.

I claim as my invention:

1. A rheostat comprising, in combination, a resistance unit and a cooperating contactor mechanism mounted for movement relative to each other, a plurality of separate resistance elements carried by said resistance unit and arranged in spaced groups, means including a contact device carried by said contactor mechanism and movable into contact with said resistance elements in one of said groups for connecting the same in common circuit relation in response to a predetermined relative movement between said unit and said mechanism, and means including a second contact device carried by said contactor mechanism in spaced relation to said first named contact device for subsequently connecting said

resistance elements of another of said groups in common circuit relation with said first named group in response to further relative movement in the same sense between said unit and said mechanism, said first named contact device having a sufficient contact area to remain in contact with said first named group of resistance elements during said further relative movement.

2. A rheostat comprising, in combination, a resistance unit and a cooperating contactor mechanism mounted for movement relative to each other, a plurality of separate resistance elements carried by said resistance unit and arranged in spaced groups, means including a contact device carried by said contactor mechanism and movable into contact with said resistance elements in one of said groups for progressively connecting the same in common circuit relation in response to a predetermined relative movement between said unit and said mechanism, and means including a second contact device carried by said contactor mechanism in spaced relation to said first named contact device for subsequently connecting said resistance elements of another of said groups progressively in common circuit relation with said first named group in response to further relative movement in the same sense between said unit and said mechanism but only after the first named contact device has been progressively moved into contact with all of the resistance elements in said first named group.

3. A rheostat comprising, in combination, a resistance unit and a cooperating contactor mechanism mounted for movement relative to each other, a plurality of individually removable resistance elements yieldably supported in said resistance unit and arranged in spaced rows, means including a contact device carried by said contactor mechanism and movable into contact with said resistance elements in one of said rows for connecting the same in common circuit relation in response to a predetermined relative movement between said unit and said mechanism, and means including a second contact device carried by said contactor mechanism in spaced relation to said first named contact device for subsequently connecting said resistance elements of the next alternate one of said rows in common circuit relation with said first named row in response to further relative movement in the same sense between said unit and said mechanism but only after the said first named contact device has been moved into contact with all of the resistance elements in said first named row.

4. A rheostat comprising, in combination, a resistance unit and a contactor unit having opposed surfaces disposed in parallel planes and mounted for movement in such planes relative to each other, a plurality of removable resistance elements carried by said resistance unit and arranged in spaced groups on said surface thereof, the elements in each group being arranged in a line, and a contactor device mounted on said surface of said contactor unit and in a position to be brought into electrical contact with said group of resistance elements, said contactor device having an edge lying in a plane parallel to said surfaces and inclined with respect to said group whereby the resistance elements in one group will be successively connected by a small 65 relative movement between said contactor device and said resistance unit.

ADDI B. CADMAN.
